UNITED STATES PATENT OFFICE.

WILLIAM THOMPSON, OF BROCKTON, MASSACHUSETTS.

WELT-GUIDE FOR WELT-SEWING MACHINES.

No. 894,989.

Specification of Letters Patent.

Patented Aug. 4, 1908.

Application filed September 1, 1904, Serial No. 222,915. Renewed January 15, 1908. Serial No. 410,994.

To all whom it may concern:

Be it known that I, WILLIAM THOMPSON, a citizen of the United States, residing at Brockton, in the county of Plymouth and State of Massachusetts, have invented an Improvement in Welt-Guides for Welt-Sewing Machines, of which the following description, in connection with the accompanying drawings, is a specification, like letters on the drawings representing like parts.

My invention is an improvement in welt guides for sewing machines used in making Goodyear welt shoes, its object being to aid in laying or conforming the welt to the curvatures of the shoe, thereby bringing less strain upon the stitches during the subsequent operations and producing a better shoe.

In making a Goodyear welt shoe, the welt is sewed to the edge of the upper and inner sole by a line of stitches passing through the extreme edge of the welt and the adjacent edges of the upper and the stitch receiving rib of the innersole, said welt being usually provided for this purpose with a longitudinal groove adjacent the inner edge of the welt on the bottom side thereof, and the sewing machine guide simply receives the welt and turns up the edge beyond said groove to receive the needle of the machine. When the welt is being sewed around curved places, particularly around the toe of the shoe, it immediately drops or is pulled into a vertical position against the side of the upper, or, in other words, it tends to assume a position perpendicular to the sole, and hence, when subsequently the sole is stitched thereto, it becomes necessary first to forcibly stretch, cut, and manipulate the welt so as to bring it flat against the sole. This brings a constant strain upon the sewing and tends to distort the parts. Accordingly, my present invention resides in providing means for compelling the welt to maintain approximately its final horizontal position while being sewed;

and to this end, in the preferred embodiment of my invention herein shown, I provide a ledge or directing plate at the rear under side of the welt guide for maintaining a considerable length of the welt in proper horizontal position while the feeding portion thereof is being sewed, the idea being to hold a sufficient portion of the welt in proper horizontal position to control, in connection with the sewing, the laying of the welt. The result is that the welt tends automatically to accommodate itself to the necessities of the curve,

whatever the latter may be, so that when thereafter the sole is applied, there is less resistance and greater pliability in the welt.

My invention will be further explained in connection with the following drawings in which I have illustrated the same as applied to one form of a welt guide, the form thereof herein shown being that of the Goodyear welt and turn shoe machine, as it is commonly known in the market, although applicable to any other kind of machine.

In the drawings; Figure 1 is a top plan view of my improved welt guide, illustrating in dotted lines the manner of use thereof, Fig. 2 is a longitudinal sectional view taken on the dotted line 2, Fig. 1, Fig. 3 is a top plan view of one form of the directing plate or welt supporting extension, Fig. 4 is a transverse sectional view taken on the dotted line 4, Fig. 1, Fig. 5 is a transverse sectional view taken on the dotted line 5—5 Fig. 3, Fig. 6 is a bottom plan view.

Referring more particularly to Fig. 1 where I have indicated the toe of a shoe *a* to which a welt has been applied about half way around as indicated at *w*, it will be seen that the welt is delivered at an angle (in practice being guided over a hook, not shown) to a guide *c* comprising a top plate *c*¹, having a lateral offset or stem *c*², terminating in an arm *c*³, adapted to be bolted to the head of the sewing machine. Secured on the under side of the plate *c*¹ is a plate *c*⁴ held by a screw *c*⁵ and turned up at its end *c*⁶ to engage the overhanging outer end *c*⁷ of the plate *c*¹ thereby forming between said plates a guideway *c*⁸ for the passage of the welt in the direction of the arrow Figs. 1 and 6, the welt being crowded outward by an adjustable finger *c*⁹ so that its edge *w*¹ beyond the groove *w*² is turned up to be sewed against the projecting edge of the upper, indicated in dotted line at *a*¹.

The foregoing parts are old and in operation result in permitting the welt to turn downwardly immediately upon being sewed. By my invention, however, I maintain the welt in an approximately horizontal position, excepting of course at the upturned edge which is receiving the stitches, and for this purpose I provide an extension *c*¹⁰, herein shown as a separate plate secured adjacent the plate *c*⁴ adjustably by a set screw *c*¹² to the stem *c*², this extension serving to support the welt, and constituting a directing plate or ledge over which the outer part of the welt must travel, as clearly shown in Fig. 1. This

plate extension is upturned at its outer edge c^{13} , where it is rounded off slightly to facilitate its use at such places as the shank, said upturned corner c^{13} serving to counteract the downward pulling tendency of the welt at the rear thereof as indicated at w^3 . The result of this extension is that the welt is compelled to maintain its horizontal position for a sufficient distance while being sewed so that the leather tends to assume the position required to cause this horizontal laying of the welt to become its normal position, instead of its abnormal position as before. For example, when rounding the toe, the welt is caused to full or pucker as much as the nature of the leather will permit at its inner edge and is caused to stretch at its outer edge. In other words this directing plate or supporting extension constitutes an automatic adjuster for compelling the welt to be sewed in such a manner that its horizontal position becomes its normal position, as far as it is possible for it to do so, in view of the nature of the welt itself.

25 Another feature of my invention resides in the shape of the slot or opening c^8 viewed transversely of the direction of feed. As heretofore constructed this slot has had more or less of a continuous curve as indicated in dotted lines at c^{14} . I have found however, that I can obtain better results in forming and stretching and shrinking the welt as above explained by having the body portion of the welt held out flat or bent upward instead of on a more or less continuous curve, as shown by said dotted lines c^{14} , and accordingly, I shape the slot to present a well defined angle or corner c^{15} , leaving the lower part of the slot c^{16} approximately flat and the upper part c^{17} at an oblique angle thereto, sufficient to receive the stitch receiving edge w^1 beyond the groove w^2 , which also facilitates the entrance of the needle n (which travels along the dotted line 2, Fig. 1).

45 This object is also greatly facilitated by rendering the edge w^1 of the welt especially flexible and normally upturned.

The adjustment c^{12} of the plate c^{11} is to accommodate different widths and kinds of 50 welts and also to adapt the guide to all classes of work, while the adjustment at c^{18} is for different thicknesses of welt.

In use, the welt is fed and sewed by the same mechanism and in the same manner as 55 heretofore; but instead of tending to turn down, when rounding the toe or any other curved surface, immediately upon being sewed, its outer edge continues to be supported flatwise until it reaches the extreme 60 outer corner of the supporting plate or ex-

tension c^{10} by which time it has received the stitches and has passed around a considerable portion of the curve to which it is being applied. The result is that it is compelled to get its shape while being firmly and positively retained in flat horizontal position and hence all the yielding of which the leather is capable is compelled to take place with relation to this flat or horizontal position of the welt. In the case of sewing about a toe, some of 65 this yielding takes place in the form of stretching of the outer edge of the welt, while some of the yielding is compelled to take place in the form of shrinking or compression of the leather along its inner edge 75 where it is being sewed, thereby affording a much better general result. Also my invention conduces to neatness and efficiency of sewing and general workmanship. A further advantage, which results from having 80 the lower portion of the opening c^8 flat and raised instead of curved in cross section, as shown in Fig. 2, is that the needle cannot possibly strike into the body of the welt but will invariably sew directly in the groove w^2 . 85

It will be understood that I am not limited to the precise construction in all cases as the extension may be varied in size and shape although I prefer the form of extension herein shown; but in some cases it is advisable 90 to form the extension integrally with the bottom plate of the guide, and also it is sometimes desirable to vary its shape and extent somewhat. Accordingly I do not intend to limit myself to all the constructional details 95 herein shown except as otherwise stated in the claims.

Having fully described my invention what I claim as new and desire to secure by Letters Patent of the United States is:—

100 In combination, a needle, a welt-guide, containing at one side of the path of said needle a guideway for the welt, and at the opposite side of the path of said needle means for supporting and maintaining the body of the welt at approximately right angles to the edge being sewed, said guideway being shaped to bend up the stitch-receiving edge at substantially a right angle to the welt-body, and said needle being arranged to 110 move back and forth above the welt-guide through said upturned edge approximately parallel to said supporting means.

115 In testimony whereof, I have signed my name to this specification, in the presence of two subscribing witnesses.

WILLIAM THOMPSON,
